FIG. 8

ATTORNEY

UNITED STATES PATENT OFFICE

GIANNI CAPRONI, OF ROME, ITALY

FUSELAGE FITTING

Application filed December 5, 1929, Serial No. 411,942, and in Italy December 10, 1928.

The object of the present invention is an attachment particularly intended to connect the longitudinal, transversal and diagonal elements of the tubular structures used in 5 aeronautical constructions.

Said structure has the purpose of simplifying the execution of the various connections, rendering them lighter and at the same time more resistant, and consists mainly in 10 forming the various parts of the structure from one, two or more sheet metal plates suitably folded, connected and soldered so as to form a main sleeve on which are subsequently fastened and soldered the connecting tubes 15 which serve for the connection with the secondary elements.

In the accompanying drawings showing schematically and by way of example three embodiments of the object of this invention:

20 Figures 1 and 2 show a first embodiment partially in view and partially in section respectively, according to two perpendicular planes;

25 Figures 3 and 4 show a second embodiment in a manner similar to the preceding one;

Figures 5 and 6 show in a like way a third embodiment, and

Figures 7 and 8 show the object of the invention applied to the construction of a flat 30 longeron represented in side view and in transversal section, respectively.

The attachment is substantially obtained (Figs. 1 and 2) by suitably cutting out a sheet metal piece which is then folded so as 35 to form the cylindrical sleeve 1 with a projecting longitudinal crown or rib obtained by overlapping the two borders 2-2, which are then soldered autogenously along the superposed borders after having placed between them a strengthening or thickening piece 4. In this rib are formed the two lugs 3, 3, provided with holes 5, 5 which serve for the passage of the bolts to which are anchored the diagonal stays.

45 The first sleeve is thus completed, and the location of the second sleeve, normal to the first one, is effected by means of a cylindrical tube 6, provided with two diametrically opposite notches to allow of the passage of rib 2, cut out at the upper portion according to

the intersection of the two cylindrical surfaces, so as to become reciprocally connected. The borders of tube 6 contacting with or connected to rib 2 and sleeve 1 are then autogenously soldered.

55 In all the figures, the same parts are indicated with the same reference numerals, with indexes varying according to the number of said parts; it is therefore apparent the structure of Figs. 3-4 and 5-6, of which the first two figures have reference to an attachment with a sleeve provided with two ribs, each with two lugs, and two connecting tubes orthogonal among themselves, arranged upon the two ribs, while the other two have reference to an attachment with a sleeve provided with three ribs, and two connecting tubes arranged upon two of the ribs each having two lugs, the third rib, to which no connecting tube is applied, having only one lug.

70 These various embodiments of the attachment serve to render possible all the connections which in practice are likely to occur in the different points of tubular structures used in aeronautical constructions, and these 75 embodiments may vary in any way whatever without departing from the fundamental idea of the invention.

Figures 7 and 8 show by way of example a flat longeron, with two orders of longitudinal elements 7-7, in which are used attachments of the type shown in Figures 1 and 2 for the connection with the transversal tubular elements 8 and the diagonal stays 9.

80 With attachments of the type shown in Figures 3 and 4 it is possible to construct prismatic longérons having four longitudinal elements, fuselage bodies and the like and the same is the case with the other embodiments.

90 Claims:

1. Attachment for the connection of the longitudinal, transversal and diagonal elements of the tubular structures used in aeronautical constructions, consisting in a main sleeve obtained by bending one or more sheet metal plates suitably, cut out, folded and joined together so as to form a cylindrical surface provided with radial ribs having anchoring lugs for the diagonal elements, on 100

one or more of the said radial ribs being arranged connecting tubes notched as far as to reach a certain extent along diametrically opposite generating lines, in order to leave a free passage for the ribs, and cut out at one end according to their intersection with the main sleeve with which they are connected.

5. Attachment according to claim 1 in which, with the object of rendering more 10 resistant the anchorage of the diagonal elements to the lugs formed in the radial ribs between the sheet metal plates, which form them, are introduced thickening and strengthening plates, cut out according to the 15 shape of the said lugs.

6. Attachment according to claim 1, in which the various connecting parts are joined together along the borders and in those points in which it is necessary, by means of autoge- 20 nous soldering.

7. Flat longéron for aeroplane consisting of two longitudinal tubular elements, which by means of the attachments according to claim 1 are connected with the tubular trans- 25 versal elements and with the diagonal stays.

8. Prismatic longéron for aeroplane formed with tubular elements running along the edges, which by means of the attachments according to claim 1 are connected with the 30 transversal elements and with the diagonal stays.

9. Flat longéron for aeroplane consisting of two longitudinal tubular elements, which, by means of the attachments according to 35 claim 1, are connected with the tubular transversal elements and with the diagonal stays and whereby between the sheet metal plates, which form the lugs of the radial ribs, are introduced thickening and strengthening 40 plates cut out according to the shape of said lugs.

10. Flat longéron for aeroplane consisting of two longitudinal tubular elements which, by means of the attachments according to 45 claim 1, are connected with the tubular transversal elements and with the diagonal stays and whereby between the sheet metal plates, which form the lugs of the radial ribs, are introduced thickening and strengthening 50 plates, cut out according to the shape of the said lugs and further the various parts are joined together along the borders and in those points in which it is necessary by means of autogenous soldering.

11. Prismatic longéron for aeroplane formed with tubular elements running along the edges, connected with the transversal elements and with the diagonal stays by means of the attachments according to claim 1 and 60 whereby between the sheet metal plates, which form the lugs in the radial ribs, are introduced thickening and strengthening plates, cut out according to the shape of the said lugs.

12. Prismatic longéron for aeroplane

formed with tubular elements running along the edges, connected with the transversal elements and with the diagonal stays by means of the attachments according to claim 1, and whereby between the sheet metal plates, which form the lugs in the radial ribs, are introduced thickening and strengthening plates, cut out according to the shape of the said lugs, and further the various parts are joined together along the borders and in 75 those points, in which it is necessary, by means of autogenous soldering.

In testimony whereof I have affixed my signature this 16th day of November, 1929,

GIANNI CAPRONI. 80
